UNITED STATES PATENT OFFICE.

JEFFERSON W. SEALE, OF MINERAL WELLS, TEXAS.

WRENCH.

1,060,862.

Specification of Letters Patent.

Patented May 6, 1913.

Application filed November 23, 1912. Serial No. 733,126.

To all whom it may concern:

Be it known that I, JEFFERSON W. SEALE, a citizen of the United States, residing at Mineral Wells, in the county of Palo Pinto and State of Texas, have invented a new and useful Wrench, of which the following is a specification.

This invention has reference to improvements in wrenches, and is designed to provide a wrench which may be particularly useful for machinists, especially in positions where a thin jaw wrench is needed, and in addition providing for the removal of parts upon which an ordinary nut wrench, even though thin jawed, would not act.

In accordance with the present invention the wrench comprises two similar members movable lengthwise one of the other with one end of the wrench shaped to engage nuts or other polygonal structures, the jaws being preferably arranged at an angle of less than ninety degrees to the length of the wrench, while at the other end the jaws are so arranged as to grip structures which are circular or rounded in cross section where smooth parallel jaws would be ineffective. The last-named end of the wrench, which may for convenience be termed a pipe gripping end, or simply a pipe wrench end, has a movable jaw construction adapting it particularly to the use for which the wrench is intended.

The invention will be best understood from a consideration of the following detailed description, taken in connection with the accompanying drawings forming a part of this specification, with the further understanding that while the drawings show a practical form of the invention, it is susceptible of other practical embodiments, wherefore the invention is not confined to any strict conformity with the showing of the drawings, but may be changed and modified so long as such changes and modifications mark no material departure from the salient features of the invention.

In the drawings:—Figure 1 is a side elevation of the wrench. Fig. 2 is a longitudinal section. Fig. 3 is a section on the line 3—3 of Fig. 1 but drawn on a larger scale. Figs. 4, 5, 6 and 7 are detail sections on the lines 4—4, 5—5, 6—6 and 7—7, respectively, of Fig. 1, but drawn on a scale similar to that of Fig. 3.

In the drawings there is shown a wrench composed of two principal members 1, 2

each in the form of an elongated flat bar, engaging edge to edge, one of the members, say the member 1, at an intermediate point having a recess 3 formed therein on the edge 60 engaging the other member, and lodged in this recess is an actuating screw nut 4 engaging teeth 5 on the other member, the arrangement being similar to the actuating devices employed in different types of 65 wrenches, and especially pipe wrenches. On one end of the member 1 is formed a jaw 6 and on the corresponding end of the member 2 there is formed a jaw 7, these jaws having matching faces 8, 9, parallel one to the other 70 and at an angle to the meeting edges of the two members 1 and 2 approximating forty-five degrees, although this angle may be otherwise related to the meeting edges of the two members. The wrench members are 75 preferably made quite thin, so that the jaws 6 and 7 may be introduced in places where a thicker type of wrench would not be received and the angle of the jaws 6 and 7 to the body portion of the wrench permits 80 its use under conditions prohibitive to an ordinary monkey wrench.

That end of the member 1 remote from the jaw 6 is formed with a jaw 10 projecting oppositely with relation to the jaw 6 and in 85 coactive relation to the jaw 10 is another jaw 11 on the corresponding end of a shank 12 connected in a manner to be described to the body member 2, which latter is shorter than the body member 1, the difference in 90 length of the two body members being made up by the shank 12 with its jaw 11. The two jaws 10 and 11 are thin and flat like the jaws 6 and 7, and these two jaws are designed to operate the same as the jaws of 95 a pipe wrench, for which reason suitable teeth 13, 14 are provided on the respective jaws. It is customary in pipe wrenches to form the teeth either directly on the respective jaws or on renewable blocks attachable 100 to the jaws, and in the drawings the latter expedient is shown, the teeth 13 being formed on a block 15 and the teeth 14 being formed on a block 16. Each of these blocks has wings 17 arranged to straddle the respective jaws 10 and 11 and to be traversed by screws or pins 18, which also traverse the jaws for holding the toothed blocks in place. Moreover, the jaws 10 and 11 are recessed, so that the blocks 15 and 16 may be inset 110 for a distance into the corresponding portions of the jaws.

The shank 12 is provided at the end remote from the jaw 11 with legs 19 on opposite sides and projecting from the shank at substantially right angles to the length thereof and so spaced as to straddle or receive between them the body member 1. The legs 19 are somewhat longer than the width of the body member 1 and project beyond the edge of the body member 1 remote from that normally engaged by the shank 12 and at the free ends the legs 19 are traversed by a pin or screw 20 in turn traversing an elongated block 21 engaging that edge of the body member 1 remote from that engaged by the body member 2, the pin or screw 20 serving as a pivot, as will herein-after appear. The legs 19 are connected to the block 21 at a point about intermediate of the length of the block. On one side of the pivot 20 the block 21 is made fast to the ends of the legs of a yoke 22 embracing the body member 1 so as to hold the corresponding end of the block 21 to the body member 1, but at the same time permitting relative sliding movements of the block 21 and the body member 1 lengthwise of the latter. The block 21 at the end remote from that carrying the yoke 22 has straps 23 made fast thereto on opposite sides of the body member 1, and these straps are of sufficient length to be made fast to the corresponding end of the body member 2, this end being recessed as indicated at 24 for a purpose to be described, so that at the end where the straps 23 are made fast to the body member 2 the latter is of less width than the main portion of the body member 2. Projecting from the shank 12 at that edge thereof remote from the edge engaging the body member 1 is a finger 25, the direction of projection being lengthwise of the shank 12, and this finger extends along the narrow end of the body member 2 in the recess 24. The finger 25 has fast thereto a spring 26 so related to the finger as to engage the body member 2 within the recess 24. The shank 12 is provided with a notch 27 accommodating the yoke 22 where passing over the body member 1 between the latter and the shank 12.

The straps 23 serve to hold the body members 1 and 2 together at the end of the body member where the straps 23 are applied, while a yoke 28 fast to the body member 1 and embracing the body member 2 adjacent the jaw 7 serves to hold that end of the body member 1 provided with the jaw 6 to the corresponding portion of the body member 2.

By a suitable manipulation of the nut 4, the body member 2 may be moved lengthwise of the body member 1 to separate the jaws 6 and 7, or the jaws 10 and 11, as the case may be, or to cause these jaws to approach. The jaws 6 and 7 are at such an angle to the length of the body members 1

and 2 as to answer the purposes of an open ended wrench under conditions which would be impossible with an ordinary monkey wrench.

The pipe wrench end of the tool is adjusted by the nut 4 and when it is desirable to use this end of the wrench the jaw 11 is turned on the pivot 20 by pressure applied to the finger 25, thus moving the jaw 11 away from the body member 1. Now, when the pipe gripping end of the wrench is applied to any object to be turned, the strain due to the action of the wrench will move the jaw 11 about the pivot 20 until the shank of the jaw is in engagement with the body member 1, especially at the point where the jaw and shank join, thus relieving the pivot 20 of strain. The pivot 20 is on the opposite side of the body member 1 from the shank 12 and therefore the movable or pivoted jaw 11 approaches the fixed jaw more rapidly than any ordinary pipe wrench, thereby greatly reducing the liability of slipping. Should the teeth 13 and 14 become worn, new blocks 15 and 16 may be substituted for the worn ones, and the wrench is at once restored to its original efficiency.

What is claimed is:—

1. A wrench comprising two elongated members of substantially equal length and slidable longitudinally one on the other, one member including a jaw in fixed relation thereto, and the other member including a jaw pivoted thereto and provided with a shank in normal alinement with the remainder of said second-named member, the pivot connection of the pivoted jaw to the second-named member being on the side of the first-named member remote from said second-named member.

2. A wrench comprising two elongated members connected together and movable one on the other in the direction of the length of the wrench, one of said members having a jaw in fixed relation thereto and the other member having a jaw with a shank on the same side of the first-named member as said second-named member, the shank of the jaw, and the corresponding end of the second-named member being each provided with a member individual thereto and extending to the side of the first-named member remote from the second-named member and jaw carried thereby and there pivotally united one to the other.

3. A wrench comprising an elongated member having a jaw formed on one end thereof, another elongated member connected to the first named member and slidable lengthwise thereof, another jaw in operative relation to the first-named jaw and provided with a shank having pivotal connections to the second named member on the side of the first named member remote from

the second named member, and a manipulating member extending from the shank of the movable jaw along the second named member in the direction of the length thereof and from the end of the shank remote from the jaw carried by it.

4. A wrench comprising an elongated member having a jaw formed on one end thereof, another elongated member connected to the first-named member and slideable lengthwise thereof, another jaw in operative relation to the first-named jaw and provided with a shank having pivotal connections to the second named member on the side of the first named member remote from the second named member, and a manipulating member extending from the shank of the movable jaw along the second named member in the direction of the length thereof and from the end of the shank remote from the jaw carried by it, the wrench being provided with a spring between the finger and the second named member and tending normally to hold the jaw end of the shank in engagement with the first named member.

5. A wrench comprising two elongated body members one of which is provided with a fixed jaw and the other of which is of shorter length than the first-named member, means for adjusting the two members lengthwise of the wrench, a jaw carried by the shorter one of the two members and pivoted thereto to move with relation to the jaw of the longer member in a direction from and toward said longer member, and means associated with the pivoted jaw and having a normal tendency to hold it against the said longer member.

6. A wrench having two elongated body members relatively movable lengthwise of the wrench, one of the members having a jaw formed thereon, a slide block movable along the member with a jaw formed thereon on the side thereof remote from the other body member, connections between the block and the second named body member uniting the block and body member in embracing relation to the corresponding portion of the first named body member, and a movable jaw in operative relation to the jaw of the first named member and provided with a shank having extensions pivoted to the block, said shank being on the side of the first named member remote from the block.

7. A wrench having two elongated body

members relatively movable lengthwise of the wrench, one of the members having a jaw formed thereon, a slide block movable along the member with the jaw formed thereon on the side thereof remote from the other body member, connections between the block and the second named body member uniting the block and body member in embracing relation to the corresponding portion of the first named body member, and a movable jaw in operative relation to the jaw of the first named member and provided with a shank having extensions pivoted to the block, said shank being on the side of the first named member remote from the block, the second named member having the end adjacent the movable jaw reduced in width and the shank of the movable jaw having a finger prolongation in overriding relation to the reduced portion of the second named jaw and also provided with a spring between the finger and the second named jaw at the reduced portion thereof.

8. A wrench comprising two elongated body members one being longer than the other, the longer member having a fixed jaw at one end, connecting means on the body members each in embracing relation to the other member to hold the body members in sliding relation, the connecting means at one end of the shorter body member including a slide block on that side of the first named body member remote from the shorter body member and the corresponding end of the shorter body member being recessed to reduce its width, the slide block being also provided with a yoke connection to the first-named member in sliding relation thereto, and a movable jaw having a shank with extensions in straddling relation to the first named body member and pivoted to the slide block between the connecting means fast to the slide block, said movable jaw being in operative relation to the jaw of the first named member at the corresponding end thereof and the shank of the movable jaw having a finger extension and a spring at the reduced portion of the second named member.

In testimony that I claim the foregoing as my own, I have hereto affixed my signature in the presence of two witnesses.
